UNITED STATES PATENT OFFICE

131,805

DESIGN FOR A COMBINATION BUILDING AND OBSERVATION TOWER

Gentil Falcão, S. Paulo, Brazil

Application April 30, 1941, Serial No. 100,716

Term of patent 3½ years

To all whom it may concern:

Be it known that I, Gentil Falcão, a citizen of Brazil, residing at S. Paulo, Brazil, have invented a new, original, and ornamental Design for a Combination Building and Observation Tower, of which the following is a specification, reference being had to the accompanying drawings, forming part thereof.

Figure 1 is a side elevational view of a combination building and observation tower showing my new design.

Figure 2 is a top plan view thereof, and Figure 3 is a side elevational view.

In the drawings, Figure 3 illustrates one side of the invention and the opposite side thereof is substantially the same as that shown in said figure.

I claim:

The ornamental design for a combination building and observation tower, as shown and described.

GENTIL FALCÃO.
